UNITED STATES PATENT OFFICE.

HENRY MILLARD FORBES, OF PORTAGE, WISCONSIN, ASSIGNOR OF ONE-FOURTH TO JESSE M. RUSSELL, ONE-FOURTH TO RICHARD H. DALTON, AND ONE-FOURTH TO FRANK THOMPSON, OF PORTAGE, WISCONSIN.

LAUNDRY DAMPENING APPARATUS.

No. 805,277.

Specification of Letters Patent.

Patented Nov. 21, 1905.

Application filed March 2, 1905. Serial No. 248,085.

To all whom it may concern:

Be it known that I, HENRY MILLARD FORBES, a citizen of the United States, residing at Portage, in the county of Columbia and State of Wisconsin, have made certain new and useful Improvements in Laundry Dampening Apparatus, of which the following is a specification.

My invention is an apparatus for use in applying steam or vapor to starched goods along the lines of fold in order that they may be folded without difficulty or any danger of breaking or unduly straining the fabric or fibers thereof.

The invention is more particularly an improvement upon the portable hand-tool for which Letters Patent of the United States No. 786,889 were granted to me April 11, 1905.

The invention is embodied in the construction, arrangement, and combination of parts hereinafter described and claimed.

In the accompanying drawings, Figure 1 is a vertical section of the entire apparatus. Fig. 2 is a vertical section of a portion of the apparatus, taken on a line at a right angle to the section illustrated in Fig. 1. Fig. 3 is a perspective view of the portion of the apparatus which chiefly embodies my present invention. Fig. 4 is a bottom plan view of the steam-discharge nozzle. Fig. 5 is a top plan view of the movable head or table upon which the goods rest while being steamed.

A indicates a rigid hollow arm standing vertical and having a horizontal foot or base a, which in practice is securely bolted to some firm support, such as a bench or table. The two parts A a are preferably cast integral, as shown. The said arm has a right-angle bend, and a detachable upturned end or head a' supports and is detachably connected with a dome or chamber B, while a steam-nozzle C is similarly attached to the under side of said head.

As shown in Fig. 1, a pipe D for induction of steam and a similar pipe E for discharge of water of condensation are arranged side by side in the hollow arm A and screwed into bores or passages d e, formed in the head a', from which vertical extensions D' E' project into the dome B. A steam-eduction pipe F is also arranged in the dome A and connected with a bore or passage f in head a', and thereby with the bore of the nozzle C. The

upper end of pipe F is adjacent to the top of the dome, and admission of steam thereto 55 may be cut off by a conical hand-valve B'. So far as described the provision for introduction into and escape of steam from the dome A is substantially the same as in my former invention; but in this case the extension E' of the water-eduction pipe into the dome A, so that its mouth is but a little below that of the steam-pipe extension D', insures the retention of water of condensation to a corresponding height, as shown at x in Fig. 65 1, whereby the dome is kept heated to a higher degree and more uniformly than before.

I have shown in Fig. 1 stop-cocks arranged below the fixed support for the apparatus for 70 the purpose of shutting off both steam and water when required.

As before indicated, I have provided, by means of the pipe extension E', for retaining a considerable quantity of water of condensation in the dome B, and I have further provided for discharge of a portion of this water through the nozzle C when conditions may require it. Such discharge is governed by a stop-cock G, (see Figs. 1 and 3,) the same being provided with a stuffing-box and its conical end entering the steam-eduction passage f, while the head a' of the hollow arm A is provided with a water-passage a'', that communicates with the hole leading into the said passage f. Thus by adjusting the valve G water may be admitted into the passage f at any time and in any desired quantity.

As shown in Figs. 2 and 4, the lower end or head c of the nozzle C is extended in opposite 90 directions and beveled or rounded on the under side to facilitate the induction of goods between it and the head or table H, as shown by dotted lines, Fig. 2, where y indicates the goods.

The head c of the nozzle is provided centrally in its under side with an elongated cavity c', which extends parallel to the longer axis of the head, as indicated in Fig. 4. The bore in the shank of the nozzle C, through which steam passes, opens at one end of the said cavity c', and a waste-pipe I is connected with the opposite end thereof and extends upward, as shown in Fig. 3. The function of this pipe will be hereinafter stated.

The vertically-movable head or table H con-

sists of a head proper, h , having a flat central portion and beveled around the edges, so that the goods held thereon may fall away from the central portion, the head being provided 5 with a narrow plate h' , (see Figs. 2, 3, and 5,) that extends across the head proper and whose ends are bent or curved down to facilitate introduction of the goods between it and the beveled ends of the nozzle-head c . The head 10 proper, h , and the aforesaid plate h' have coincident openings h^2 , that also coincide with the aforesaid cavity c in the head of the nozzle C. The head proper, h , is attached to a pipe J, which is adapted to slide vertically in guides 15 whose construction and arrangement are as follows: A tube K (see Fig. 1) is fixed in a socket a^2 , provided in the base or foundation plate a and is seated upon a disk z , having a central bore that receives the pipe J and allows it to slide freely therein. On the upper 20 end of the tube K is fixed a head L, having an opening similar to the disk z , through which the pipe J is similarly adapted to slide. By this means I provide a rigid support and vertical guide for the pipe J, with which the movable head or tube H is detachably connected by a screw-joint, as shown. Between the movable and fixed heads H and L is arranged a spiral spring M, which serves to support 25 the movable head H normally in contact with the head c of the nozzle C, as shown in Fig. 3. In order to prevent rotation of the movable head on fixed head L, so that the opening or slot h^2 may be kept in due registration with the cavity c of the nozzle C, I provide the pipe J with a feather j , which is adapted to slide in a corresponding lateral extension of the hole in the fixed head L. The head proper, h , of the movable head or 30 table is provided with a downward cylindrical extension h^3 , which incloses the spring and extends over a portion of the fixed head L, so that goods are prevented from contact with the spring and a more ornamental effect is obtained. 35

In operating the apparatus the stop-cocks of pipes D and E are opened. Then steam discharges into the dome B from the head of the extension D' and striking against the sides 40 of the dome will be deprived of its moisture to a certain extent, the drier steam entering the pipe F and discharging from the nozzle-head c upon the goods placed between the nozzle-head and the depressible head or table H. Steam thus applied to the goods along 45 the line of intended fold of the same will duly soften the fabric, so that it may be folded without danger of breaking its fibers and without impairing the gloss finish to an appreciable extent. It is apparent that since the spring M presses the movable head H upward against the nozzle C with considerable force the surplus steam—that is to say, steam which penetrates the goods—will for the most part 50 escape through the opening h^2 in the head, 55

and thus enter the pipe J, by which it is conveyed into the fixed discharge-pipe j' , forming a continuation thereof. (See Fig. 1.) The steam thus discharged upon the goods will affect the same only along the line of the cavity c and the corresponding slot h in the opposed parts, and the goods may thus be made pliable to any required degree, since the amount of steam discharged may be regulated by the operator according to his experience and judgment. If the goods are unusually thick or the starch renders them unusually stiff, so that the addition of a small quantity of water may be desirable, it may be admitted by manipulating the valve G, Figs. 1 and 3. When no 60 goods are inserted between the nozzle C and the table H, steam flows directly downward and escapes through the pipe j' ; but when goods are inserted between the parts C H the course of the steam is diverted laterally, so 65 that it passes into the lateral waste-pipe I. It will be understood that this pipe I may be arranged to discharge at any suitable point. In this instance for convenience only it is shown attached to and supported by the hollow arm. 70 It will be understood that the spring-support for the movable head H provides for the easy introduction of goods of varying thickness between the said head and the head of the nozzle and for sliding the goods between them 75 while held in the elastic clamp. It will be understood that after use of the apparatus in the manner described the goods may be passed between pressing and polishing rolls for laying the fold in the required manner. 80

The apparatus is adapted for use in laundries, and particularly by shirt-collar finishers.

Having thus described my invention, what I claim as new, and desire to secure by Letters 105 Patent, is—

1. The improved apparatus for the purpose specified, comprising a foundation plate or base, adapted to rest upon a horizontal support, a hollow arm rigidly connected with said base, a steam dome or chamber supported upon the arm and having a pendent nozzle for escape of steam, a steam-pipe whose upper portion is extended into the dome and a pipe for discharge of water of condensation having also 110 a vertical extension in said dome, the mouth thereof being below the point of discharge of steam from the steam-pipe, whereby a considerable quantity of water of condensation is retained in the dome, as and for the purpose 115 specified.

2. In an apparatus for the purpose specified, the combination with a steam dome or chamber having a pendent nozzle, of a steam-induction pipe extended vertically in the dome, and 120 a pipe for discharge of water of condensation which is extended above the bottom of the dome but to a lower height than the steam-pipe, as and for the purpose specified.

3. In an apparatus for the purpose specified, 130

the combination with a steam-dome having a pendent nozzle and a pipe communicating therewith and extending into the upper portion of the dome, a passage leading downward 5 from said dome and communicating with the passage leading to the nozzle, a valve applied at the junction of the two passages for controlling discharge of water into the nozzle, and pipes for conducting steam into said dome and 10 water of condensation therefrom, substantially as described.

4. In an apparatus for the purpose specified, the combination with a steam dome or chamber having a pendent nozzle, a steam-pipe leading 15 thereto, and a second pipe for discharge of water of condensation, the same being extended above the bottom of the dome, a third pipe for conducting steam to the nozzle, and a valve for regulating the passage of steam through 20 said pipe, substantially as described.

5. In an apparatus for the purpose specified, the combination with a fixed steam-discharge nozzle, of a head or table arranged directly under the nozzle and serving to support the 25 goods, said head having a pendent cylinder, a fixed head and a spring interposed between the two heads which are provided with aligned steam-passages, substantially as described.

6. In an apparatus for the purpose specified, 30 the combination with a fixed steam-discharge nozzle, of a vertically-movable spring-supported head, a tube fixed thereto in vertical alignment with the nozzle, a fixed head and a rigid support therefor, the said tube being guided in the fixed head, substantially as described.

7. In an apparatus for the purpose specified, 35 the combination with a fixed steam-discharge nozzle, of a vertically-movable head or table for supporting the goods, the same being arranged below the nozzle and provided with

an opening coincident with that in the nozzle, a 45 slideable tube having a fixed connection with the movable head, and guides for such tube comprising an apertured disk and a fixed base-piece in which the same is fitted, a fixed head supported adjacent to the movable head and having a central opening in which the tube of the head is adapted to slide, and a spring for supporting the movable head normally in contact with the nozzle, substantially as described. 50

8. In an apparatus for the purpose specified, the combination with a fixed steam-discharge nozzle, and a fixed head arranged below and in 55 alignment with the nozzle, a movable head arranged between the nozzle and the fixed head, and a spring interposed between the two heads, whereby the movable head is supported normally in contact with the nozzle but adapted 60 to yield to the goods inserted between them, substantially as described.

9. In an apparatus for the purpose specified, the combination with a fixed nozzle, of the vertically-movable spring-supported head or table for supporting goods, the same being beveled around the central portion and having a transverse part provided with a central opening and downwardly-curved end portions, substantially as described. 65

10. In an apparatus for the purpose specified, the combination with a goods-supporting head or table, of a nozzle having a cavity in the under side of its head, and the steam-passage that communicates with one end of said 70 cavity, and a pipe leading from the other end of the cavity, substantially as described. 75
